J. BRANDSTETTER

VEHICLE CLEANER

Filed May 12, 1924

UNITED STATES PATENT OFFICE.

JOSEF BRANDSTETTER, OF CHICAGO, ILLINOIS.

VEHICLE CLEANER.

Application filed May 12, 1924. Serial No. 712,517.

To all whom it may concern:

Be it known that I, JOSEF BRANDSTETTER, citizen of the United States, residing at Chicago, in the county of Cook and State 5 of Illinois, have invented certain new and useful Improvements in a Vehicle Cleaner; and I do hereby declare the following to be a full, clear, and exact description of the invention, such as will enable others skilled 10 in the art to which it appertains to make and use the same.

My invention relates to air-sucking or air-blowing appliances adapted to be detachably secured to vehicles and arranged so as to be actuated from a driving wheel of the vehicle. Generally speaking, the objects of my present invention include those of providing an exceedingly simple and easily attached appliance for this purpose and one 20 having certain parts so arranged as to compensate for irregularities in the running board from which the appliance is supported, and to insure a rigid supporting of the body member of the appliance while also 25 affording a sufficient yielding at the driving connection to compensate for irregularities in the tire of the driving wheel. Furthermore, my invention aims to provide an appliance of this kind which can be operated 30 with equal facility as a vacuum cleaner and as an air blower or spray device. Still other and also more detailed objects will appear from the following specification and from the accompanying drawings, in which—

Fig. 1 is a fragmentary side elevation of an automobile, showing an embodiment of my invention attached to the same in operative position.

Fig. 2 is an enlarged perspective view of 40 the same appliance, with the portion of a suction hose attached to the same.

Fig. 3 is an enlarged rear view of the appliance as it appears looking away from the vehicle, with the tire of the adjacent 45 wheel shown in dotted lines but with other vehicle portions omitted.

Fig. 4 is an enlarged zigzag vertical section taken along the correspondingly numbered line of Fig. 1.

Fig. 5 is a plan view of the same appliance, showing this attached to a running board after the manner of Fig. 1, with the rear fender of the vehicle cut away.

Fig. 6 is an enlarged transverse section

through the drive pulley of the appliance, 55 taken along the correspondingly numbered line of Fig. 2.

Fig. 7 is a front elevation of the same appliance, showing this as it appears when connected to an air blowing hose, the adjacent hose portion and the coupling for connecting the hose to the fan casing being shown in section.

In the embodiment of the drawings, the appliance of my invention includes as a 65 rigid body member a fan casing 1 attached to a clamp formed to afford a fork straddling the outer edge of the running board 2 of the automobile. The clamp portion of this body member desirably has a relatively 70 long vertical riser portion 3 adapted to bear flatwise against the outer edge of the running board and connecting an upper jaw 4 with a lower jaw 5, these jaws being spaced from each other by a distance greater than 75 the usual thickness of such running boards. Threaded through the upper jaw 4 is a thumb screw 6 which desirably has a presser foot 7 swiveled to its tip and adapted to bear against the upper face of the running 80 board. Threaded upwardly through the lower web 5 are a plurality of adjusting screws 8 adapted to engage the lower face of the running board. These adjusting screws preferably have their axes disposed 85 at the corners of an imaginary triangle, after the manner indicated in dotted lines in Fig. 5, with the clamping screw 6 and its presser foot opposite the center of this triangle. 90

The rigid body member also includes a bearing 9 which is here shown as integral with the rear face of the fan casing 1 and as forming a fork so as to afford two bearings for a shaft 10 which extends through 95 the fan casing and carries the fan 11.

To rotate the fan, I provide a pulley 13 which is fastened to the shaft 10 and which is disposed for engaging the periphery of the tire 14 of the rear driving wheel of the 100 automobile when the clamp is secured to the running board adjacent to the rear fender 15.

To insure a good frictional driving connection between the tire 14 and the pulley 13 in spite of irregularities in the latter, I desirably provide the pulley with a radially compressible core 16 interposed between the shaft 10 and an outer rim portion of the pul-

ley, as for example by employing a spongy rubber or otherwise porous grade of rubber for this core 16.

When my appliance is to be used as a vacuum cleaner, I attach a suction hose 17 to the axial port 18 of the fan casing, and provide the free end of the hose with a suction nozzle of any usual type, such as the nozzle 19 of Fig. 1. When the appliance is 10 to be used in this manner, the rear driving wheel is disposed so as to be out of engagement with the floor or ground, which may readily be done either by jacking up this driving wheel or by halting the automobile in a position in which this wheel is disposed over a depression of some kind. Then, 15 when the engine is started with the usual clutch in position for rotating the driving wheels in the proper direction, the rotation 20 of the rear driving wheel will rotate the fan shaft at a relatively much higher speed, and by suitably proportioning the size of the drive pulley 13 to the average size of the rear wheels of automobile, I can readily 25 secure such a speed of fan rotation as will produce a strong suction through the hose 17.

When my appliance is to be used for air-blowing purposes (which is often desirable 30 both for blowing foreign matter out of crevices, atomizing and spraying oil against the engine, etc.), I change the hose connection from the axial port 18 to the port 12 which formed the discharge outlet of the fan casing 35 when the appliance was employed as a vacuum cleaner, so as to connect the hose after the manner shown. With this in mind, I desirably make the end portion of this port 40 12 cylindrical and provide it with a pair of oppositely directed projecting pins 20 adapted to interlock with bayonet catches on a reducing nipple 21 to which the inlet end of a blower hose 22 is attached, as shown in Fig. 7.

45 In initially adjusting my appliance to any particular car, the adjusting screws 8 are backed down considerably so as to clear the bottom of the running board, thereby permitting the clamp of the appliance to be slid 50 longitudinally along the running board with the presser foot 7 slidably bearing on the top of the running board until the pulley 13 is in good frictional engagement with the wheel tire 14, this being done with the riser 3 bearing 55 flatwise against the outer edge of the running board. When this position has been reached, the screws 8 are tightened, thereby permitting the several screws 8 to compensate for irregular formations on the

bottom of the running board. This adjustment need only be made once for a given car, after which the hand manipulation of the clamping screw 6 is ample, so that no tools whatever are required in using my appliance after its initial adjustment has been made. 60 65

However, while I have heretofore described my invention as embodied in a commercial form having numerous highly desirable details of construction and arrangement, I do not wish to be limited as to these, 70 since many changes might obviously be made without departing either from the spirit of my invention or from the appended claims.

I claim as my invention:—

1. A vehicle cleaner including a body having spaced upper and lower jaws formed to engage on opposite sides of the running board of a vehicle, means to clamp the jaws to the running board, an operating mechanism having a casing, said body having an integral part extending outwardly therefrom and at an angle, and rigidly connected to said member so as to support the latter at points along the side and in spaced relation to the rear end of the running board, said body having an elongated wall in the space between the jaws to engage the outer edge of the running board so as to engage against the outer side edge of the latter, a forked bearing carried by the inner side of said casing of said mechanism and extending in the space between said rear end of the running board and the adjacent rear wheel of the vehicle, and a driving member for actuating the operating mechanism journaled in said bearing and being engageable with said rear wheel of the vehicle. 80 85 90 95

2. A vehicle cleaner including a body having spaced upper and lower jaws formed to engage on opposite sides of the running board of a vehicle, means to clamp the jaws to the running board, an operating mechanism having a casing, said body having an integral part extending outwardly therefrom and at an angle, and rigidly connected to said member so as to support the latter at points along the side and in spaced relation to the rear end of the running board, a shaft connected to the operating member and extending in the space between said rear end of the running board and the adjacent rear wheel of the vehicle, and a member on the shaft engageable with said rear wheel of the vehicle to be actuated thereby. 100 105 110 115

Signed at Chicago, Illinois, May 9th, 1924. 115

JOSEF BRANDSTETTER.
